(57) **CLAIM**

The ornamental design for a vaporizer, as shown and described.

DESCRIPTION

FIG. 1 is a perspective view of an upper side of a vaporizer in accordance with the present invention, which perspective view includes a view of a first end and a first side wall of the vaporizer.

FIG. 2 is another perspective view of the upper side of the vaporizer of FIG. 1, which perspective view includes a view of the first end and a second side wall of the vaporizer.

FIG. 3 is another perspective view of the upper side of the vaporizer of FIG. 1, which perspective view includes a view of a second end and the second side wall of the vaporizer.

FIG. 4 is another perspective view of the upper side of the vaporizer of FIG. 1, which perspective view includes a view of the second end and the first side wall of the vaporizer.

FIG. 5 is another perspective view of a bottom side of the vaporizer of FIG. 1, which perspective view includes a view of the second end and the first side wall of the vaporizer.

FIG. 6 is another perspective view of the bottom side of the vaporizer of FIG. 1, which perspective view includes a view of the second end and the second side wall of the vaporizer.

FIG. 7 another perspective view of the bottom side of the vaporizer of FIG. 1, which perspective view includes a view of the first end and the second side wall of the vaporizer.

FIG. 8 is an elevational view of the first end of the vaporizer of FIG. 1.

(Continued)

FIG. 9 is an elevational view of the second end of the vaporizer of FIG. 1.

FIG. 10 is an elevational view of the first side wall of the vaporizer of FIG. 1; and,

FIG. 11 is an elevational view of the second side wall of the vaporizer of FIG. 1.

In the drawings, the broken lines depict portions of the vaporizer that form no part of the claimed design.
